UNITED STATES PATENT OFFICE.

JOHN FROELICH, OF FROELICH, IOWA.

GAS-ENGINE.

SPECIFICATION forming part of Letters Patent No. 550,266, dated November 26, 1895.

Application filed February 23, 1893. Serial No. 463,300. (No model.)

To all whom it may concern:

Be it known that I, JOHN FROELICH, a citizen of the United States, residing at Froelich, in the county of Clayton and State of Iowa, 5 have invented a new and useful Improvement in Gas or Explosive Engines, of which the following is a specification.

The objects of my invention are to provide a better governing apparatus and mechanism 10 for supplying the gasoline to the carburetor when gasoline is used; and the invention consists in the mechanical elements and combinations set forth in the claims hereof.

Figure 1 is a side view of the engine down 15 to the bed-plate or supporting-frame. Fig. 2 is a plan view. Fig. 3 is a side sectional view. Fig. 4 is a sectional view through the cylinder and carburetor on the line $y-y$. Fig. 5 is a side view showing the exhaust-valve 20 mechanism in one position. Fig. 6 is the same with it in another position. Fig. 7 is the same with it in another position. Fig. 8 is a sectional view through the carburetor supply-valve. Fig. 9 is an end sectional view 25 of the same.

In the drawings, A designates the supporting-casting, and A' the bearings supporting the engine-shaft B, with its crank B'. On this shaft B there is a band-wheel B², from 30 which by a band the governor is driven, and on this shaft B there is a cam B³, actuating the exhaust-valve, and there is also a cam B⁴, actuating the electrical sparking device. Supported on the frame A by posts a there is 35 a cylinder-casting C, which is water-jacketed, having the water-cavity C', with entrance and exit pipes C² C³. In this cylinder C there is the ordinary gas-engine piston C⁴, connected by pitman C⁵ to crank B'. From the top of 40 the cylinder C there is a passage-way C⁶, leading to the exhaust and supply valves.

The ordinary action of a gas engine is what is termed "four-cycle"—that is, on a downward movement of the piston the suction thereby 45 created fills the cylinder with the explosive gas and on the upward movement this is compressed and at the proper moment is exploded, which drives down the piston, and on the following upward movement the burned 50 gases are exhausted out of the cylinder, when the same action again occurs, so the engine takes gas only at every other down stroke, and

in governing the engine it has been found best to give the engine a full supply of gas at each explosion and limit the speed of the 55 engine by limiting the explosions, so the governor governs by cutting off entirely the gas supply.

This engine is here shown as being supplied by gas generated from gasoline, but any suitable gas may be used, and the gas is exploded by an electric sparker E, which is mounted on a shaft e and is connected to one pole of an electric battery and revolves past the end of the other pole E of the battery, and 60 the shaft e is driven by a ratchet E², driven by a pawl E³, held in engagement by spring e³ and pivoted at e' to a lever E⁴, pivoted at e² to the frame A and carrying a roller E⁵, working on cam-wheel B⁴. The gas-supply valve is designated by G and is operated by suction like any ordinary suction-pump valve, the suction of the cylinder lifts it and it is held down by a spring G' on its stem g, and the spring is adjusted by nuts g'. This valve opens to cavity 70 G² leading to the carburetor, and its entrance to the carburetor has a check-valve G³ to insure safety against the explosion passing to carburetor. The carburetor is composed of a vertical cylinder D, across which at intervals 80 there are fixed a series of wire-gauze screens d, and it is open at the base, around which there is a basin D' larger than the cylinder D and open to the outer air. The object of the basin is to catch any non-volatile oil that 85 may pass the carburetor.

D² designates the gasoline-supply pipe, which connects to a valve F in the top of the carburetor. This valve is shown in Figs. 4, 8, and 9 and consists of a chamber F', which 90 measures the supply of gasoline discharged into the carburetor for making gas for one explosion. The size of this chamber is regulated by the plug F², which is threaded into the chamber F' and adjusted by the rosette-wheel F³. This chamber F' is opened to be filled from the pipe D², and opened to be emptied to the carburetor by the oscillating valve-block F⁴, which has a chamber f opening and closing the chamber F' to the pipe D², and 100 has a chamber f', opening and closing entrance to carburetor. In the position shown in the drawings, the chamber F' is being filled by the pipe D²; but by the oscillation of the

blocks F⁴ this entrance is closed and the chamber F' opened to the carburetor, and the gasoline drops on the screens d, and the air passing up through by the suction of cylinder, 5 converts the gasoline into gas. The exhaust-valve is shown as H, with its stem h, and is held down by a spring H', working against a block h' on the stem h. The lower end of the stem h is held by a keeper h². This valve 10 H is lifted every other stroke by the rod I, pivoted at i to a link I', pivoted at i' to post a, and carries a roller I², working on cam-wheel B³. The upper end i² of the rod I is guided to alternately strike and miss the valve-stem 15 h by the roller I³, guided in ways i³ i⁴, fixed in position from the cylinder-casting, and guided on said ways by a spring i⁵, attached to a rocking block I⁴, which is pivoted at i⁶, Fig. 3, to the cylinder-casting C. This block I⁴ is locked 20 in its position by a spring-actuated locking-bar I⁵, pivoted at i⁷ to the cylinder-casting, and is held down by spring i⁸ and has notches i⁹ i¹⁰, into which a projection i¹¹ of rocking block I⁴ engages. 25 The position of the rod I in Fig. 1 is at the point of commencing its upward stroke when it strikes the valve-rod h and lifts the valve H, making the exhaust.

Fig. 5 shows the position of the rod I on its 30 return movement, but not quite home. The rod I in passing up as in Fig. 1 is guided by the roller I³, guided by ways i³ and spring i⁵ to strike the valve-rod h, and in passing up a projection i¹³ on rod I strikes projection i¹² 35 on rocking block I⁴ and rocks it from the position shown in Fig. 7 to that shown in Figs. 5 and 6, in which movement the spring i⁵ springs from contact with the way i⁴ to that of i³, and on the descent of the rod the spring 40 i⁵ yields and lets the roller I³ pass by, and on the upward stroke, Fig. 6, guides it up against the way i⁴, when the end of the rod I will miss the valve-rod h and make no exhaust; but in passing up on the stroke Fig. 6 the projection 45 i¹⁴ will strike projection i¹⁵ and thereby rock the block i⁴ to position of Fig. 7 from Figs. 5 and 6, and on return the spring i⁵ yields and lets the roller I³ pass. Thus every other stroke the rod I strikes the valve-stem h and 50 lifts the exhaust-valve and effects the exhaust.

The governor K is here shown as that of an ordinary ball-governor driven by a belt k from the engine-shaft, and in governing lifts 55 the arm K' of a lever pivoted at k' on the cylinder-casting and provided with a locking projection k³, which by the action of the governor is advanced to engage the projection h' on the valve-stem h and hold open the exhaust-valve during the time the speed exceeds that desired. Thus as the exhaust-valve is held open the suction of the piston draws in the outer air through the exhaust port and does not draw a supply of gas for a new explosion. This drawing in and out of the outer air is a desideratum, as it cools the cylinder 60

and permits a free action of the engine, giving no strain to resist the engine or to displace the valve mechanism.

In other engines where the valves are operated regularly by positive mechanism the cutting off of the gas supply causes the engine to pump against closed valves, producing resistance to the motion of the engine, and puts strains on the valve mechanism not otherwise produced. The gasoline-supply valve F is operated by an arm f² on its axis, pivoted to a link f³, pivoted to lever f⁴, pivoted at f⁵ to cylinder-casting, which lever f⁴ engages a projection f⁶, Fig. 3, on exhaust-valve stem h. 70 Thus the action of the exhaust-valve operates the supply of gasoline to the carburetor, and as the exhaust-valve is controlled by the governor, so the supply of gasoline is controlled by the governor. Heretofore in engines of 75 this class the gasoline supply to the carburetor has been regulated by a throttle valve adjusted by the operator to supply an average uniform flow sufficient for the work of the engine and at the interval that the governor 80 shuts off the gas supply to the cylinder the gasoline keeps running to the carburetor, and then the next charge of gas to the engine is heavier than the regular charge and does not produce as good a result, and the governor 85 governs only the speed of the engine and does not, by shutting off the gas supply, save in the consumption of gasoline, while with our mechanism the amount of gasoline to make an explosion is regulated by the operator by the 90 adjustment of the size of the chamber F', and this is emptied into the carburetor under the control of the governor; so if no gas is taken 95 no gasoline is supplied to the carburetor, which is a desideratum.

What I claim is—

1. The combination with the engine cylinder and piston, of a carburetor, a chamber of adjustable capacity for holding a charge for the carburetor, an exhaust valve, means for operating the latter, a governor arranged to hold said valve open when the speed is too great, and mechanism operated by the movement of said valve to empty said chamber into the carburetor.

2. The combination with an engine cylinder, an ignition chamber, an intermediate passage, a carburetor, and a source of supply, all communicating in sequence, of suction-operated valves between the chamber and passage 110 and between the passage and carburetor, a mechanically operated valve between the carburetor and source of supply, an exhaust valve opening said chamber, an engine governor, and devices whereby the governor at high 115 speed holds the exhaust valve open and prevents the opening of said mechanically operated valve.

3. A gas engine having valve operating mechanism consisting essentially of a cam B³ 120 a rod I a rocking block I⁴ pivoted to the engine frame, mechanism for shifting the posi-

tion of block I^4 at every revolution of the engine and mechanism for locking block I^4 in position substantially as shown.

4. A gas or explosive engine, having valve operating mechanism consisting of a cam B^3 , a rod I actuated by said cam and the end adjacent to said cam held in position by an oscillating bar I' and the other end of said bar I guided in its movement, to strike the valve stem h , at every alternate revolution of the

engine, by mechanism pivoted to the engine frame and oscillated at every stroke of the rod I as shown.

In witness whereof I have hereunto subscribed my name in the presence of two witnesses. 15

JOHN FROELICH.
